(57) **CLAIM**

The ornamental design for a bottle cap for a squeeze bottle, as shown and described.

DESCRIPTION

FIG. 1 is a side view of a bottle cap for squeeze bottle, showing our design;

FIG. 2 is a top view thereof;

FIG. 3 is front view thereof;

FIG. 4 is a rear view thereof;

FIG. 5 is a bottom view thereof;

FIG. 6 is a perspective view thereof;

FIG. 7 is an opposing perspective view thereof; and,

FIG. 8 is a perspective view thereof, in use condition.

In the drawings, the broken lines depict environmental subject matter only and form no part of the claimed design.
